Atherton R. Mitchell, San Francisco, Calif., assignor to
Renaud International, Ltd., Fitchburg, Mass., a corpo-
ration of Delaware

Filed Oct. 5, 1967, Ser. No. 8,868

Term of patent 14 years

(Cl. D57—1)

FIG. 1

FIG. 2

FIG. 3

FIG. 1 is a front elevational view of a sunglasses front showing my new design.

FIG. 2 is a top plan view thereof.

FIG. 3 is a side elevational view thereof.

The rear of the sunglasses front, not shown, conforms in configuration to the front shown.

The side not shown has substantially the same appearance as the side shown.

The dominant features of my design reside in the portions shown in full lines.

I claim:

The ornamental design for a sunglasses front, substantially as shown and described.
